JAMES E. LYNCH, OF TEXARKANA, TEXAS

HYDRAULIC GEAR PULLER

Application filed December 31, 1929. Serial No. 417,772.

This invention relates to pulling devices, more particularly a device for pulling gears or the like.

The primary object of the present invention is to provide a gear puller by means of which a steady, smooth and powerful pulling force may be applied to a gear to remove the same from its supporting shaft.

The invention broadly contemplates the provision of a pulling device employing fluid pressure, wherein a cylindrical body is provided having a piston in and extensible from one end thereof with means operated from the other end of the cylinder for injecting a liquid such as oil or water into the cylinder behind the piston to force the same outwardly against the end of a shaft, gear-engaging arms being disposed upon opposite sides of the cylinder and adjustably connected therewith through the medium of a shiftable collar mounted thereon.

Still another object of the invention is to provide a pulling device wherein the collar above referred to may be easily and quickly coarsely adjusted with respect to a gear, so that the piston element need only be moved a relatively short distance to effect the removal of the gear.

Another object of the invention is to provide a new and novel means for mounting an arm-carrying collar in place upon the cylinder of the device, whereby quick assembly of the structure may be brought about.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in side elevation of the gear puller embodying the present invention showing the same applied;

Figure 2 is a sectional view taken on the line 2—2 of Figure 1;

Figure 3 is a transverse sectional view taken upon the line 3—3 of Figure 1;

Figure 4 is a sectional view through the pulling arm supporting collar and the split nut associated therewith;

Figure 5 is a transverse sectional view through the collar and nut shown in Figure 4; and

Figure 6 is a view partly in section and partly in side elevation of a modified construction of the gear-engaging bars and method of connecting the same with the pulling arms.

Referring more particularly to the drawings, wherein like numerals of reference indicate corresponding parts throughout the several views, the numeral 1 indicates the body of the gear puller embodying the present invention, which body as shown is in the form of a cylinder open at each end and having removably positioned therein adjacent one end, the forward end, the partition plate 2 through the center of which an aperture 3 is formed. The wall of the cylinder 1 between the partition plate 2 and the adjacent end is materially thicker than the rest of the cylinder wall, the chamber 4 thus formed in the forward end of the cylinder by the use of the plate 2 housing a piston body as shown.

The inner face of the cylinder wall adjacent the open forward end thereof is provided with the rib 6 which snugly engages about the piston 5, and the inner face of the wall from this rib to the adjacent end thereof is screw-threaded as indicated at 7 to receive the packing nut 8 which surrounds the piston and maintains the packing material 9 firmly in position thereby.

The forward end of the piston 5 is pointed or of cone formation as indicated at 10 and the rear end thereof has secured thereto the plate 11 and washer 12, by means of a screw 13 passing therethrough and into the rear end of the piston. As shown the plate is of greater diameter than the piston body so that it will come into contact with the inner side of the rib 6 when the piston is moved forwardly in the chamber 4 and thus prevent

the complete escape of the piston therefrom. The rear face of the partition plate 2 has formed thereon around and concentric with the aperture 3 an interiorly threaded collar 14 and adjacent the edge of the plate there is formed a sleeve 15 which communicates at its inner end with an aperture 16 formed through the partition plate in the manner shown, the wall of this sleeve having a lateral opening 17 therethrough for the purpose hereinafter to be described.

Threadably secured in the rear end of the cylinder 1 is a head plate 18 through the central portion of which opens one end of a piston guide 19 which, when the head plate 18 is in place, extends through the cylinder to and is engaged in the collar 14 in the manner shown.

The inner end of the tube 19 is normally closed by a spring-pressed check ball 20, the spring therefor being interposed between the ball and the partition 2 so that as will be readily seen the passage of a fluid past this check will be permitted only from the rear portion of the cylinder into the chamber 4 in which the piston is housed, the fluid of course being confined between the partition 2 and the rear end of the piston 5 in the manner shown. Opening through the side of the tube 19 adjacent the check 20 is an inlet opening 21, this opening being controlled by the inlet check valve 22 which, as shown, only permits fluid to pass from the interior of the cylinder into the tube 19.

Reciprocably mounted in the tube 19 is a small piston 23, the forward end of which is provided with a suitable washer 24 while the rear end passes through a packing 25 maintained in the enlarged outer end of the tube 19 by a packing nut 26.

At its outer end the piston 23 has a loose connection as at 27 with a lever 28, this connection being inwardly of one end of the lever the adjacent end thereof being pivotally secured as at 29 to a suitable post 30 carried by the head plate 18.

Extending through and threadably retained in a bore 31 formed through the head plate 18 is a needle-valve stem 32 the pointed inner end of which extends into the sleeve 15 to close the passage 16 through the plate 2, the outer end of this needle-valve stem carrying a knurled head 33 by which it may be grasped for rotation as necessary. In order to facilitate the introduction of oil or water into the cylinder 1 without the necessity of removing the head 18, a plugged aperture 34 is provided through the head plate as shown.

The cylinder 1 is provided exteriorly with screw-threads 35 which extend throughout the length thereof as clearly shown in Figure 1. Engaged about the cylinder is a two-part frusto-conical nut 36, the parts thereof being pivotally secured together as at 37 so that the parts of the nut may be readily separated

for removal but maintained in connected relation so that replacement thereof may be easily effected.

Adapted to receive and surround the split nut 36 is a tapered collar 38 which carries the diametrically oppositely positioned and extended pairs of arms 39, each pair of arms being provided upon the outer edges thereof with the transverse notches 40.

As shown in Figure 3 the arms of each pair are arranged in spaced parallel relation, and when the puller is in operation there is disposed between the same a pull-bar 41, the outer end of which is provided with a cross-head 42 which extends across the arms and engages in certain of the notches 40. The opposite ends of these bars 41 are hooked as indicated at 43 to facilitate their connection with a gear member, such a gear being shown and indicated by the numeral 44.

In operation the cylinder 1 is directed toward the end of the shaft 45 carrying the gear to be removed, the pointed end of the piston 5 being placed upon the longitudinal center thereof. A coarse adjustment of the split nut and collar is then quickly made to place the arms 39 substantially in the right position for the hooked ends 43 of the pull-bars 41 to conveniently engage behind the gear, the cross-head of each bar being already coupled with and extending transversely of a pair of the arms. With the puller thus positioned the lever 28 is actuated to reciprocate the piston 23, this operation causing the fluid in the rear portion of the cylinder to be drawn through the check valve 22 and discharged through the check 20 into the chamber 4 behind the piston 5. The piston is of course compelled to move out of the chamber 4 against the end of the shaft 45 and thus exert a pull upon the rods 41 which will result in the removal of the gear from the shaft. During the foregoing operation the pointed forward end of the needle-valve stem 32 will, of course, be firmly positioned in the bore 16.

Following the removal of the gear the stem 32 is rotated to open the bore 16 and allow the compressed fluid to flow back into the rear end of the cylinder 1, the return movement of the piston 5 being effected in any suitable manner, such for example as by the application of pressure to the pointed end thereof.

In Figure 6 a slight modification of the structure thus far described is shown, this modification being in connection with the pull-rods by means of which the arms 39 are coupled with the gear 44. Some gears are provided with apertures through the web portion lying between the hub and the toothed rim thereof, and under some conditions it might be preferable to engage the pull-rods in these apertures instead of hooking them over the edge of the gear. For this

purpose I provide the threaded pull-rods 46 upon the forward ends of which nuts 47 may be mounted after the forward ends of the rods have been extended through the 5 apertures in the gear body. The other ends of the rods are then located between the arms 39 and receive thereon washers 48 and nuts 49, the washers 48 extending across the space between the arms and thus preventing 10 the nuts from being pulled therethrough. The other parts of the gear-puller structure are the same as described in connection with Figures 1 to 5 inclusive.

From the foregoing description it will be 15 readily seen that with a puller of the character herein described a slow, smooth, and powerful pull may be applied to a gear without the expenditure of a material amount of energy on the part of the user of the device.

20 It will also be appreciated that the present gear puller will enable the user to perform an operation quickly because of the manner in which a quick rough adjustment of the arms may be made by shifting the collar and opening 25 the split nut so that it may be moved longitudinally of the cylinder independently of its threaded engagement therewith.

Having thus described my invention, what I claim is:—

30 1. A gear puller comprising a cylinder having a partition therein adjacent one end forming a piston chamber, a piston within said chamber extensible through the adjacent end of the cylinder for engagement with a gear- 35 supporting shaft, the cylinder upon the other side of the partition being adapted to contain a fluid, a tube within the fluid containing portion of the cylinder having a valved inlet from the cylinder adjacent the partition and 40 a valved outlet through the partition into said chamber, a piston within said tube, said cylinder being exteriorly threaded throughout, a two-part collar surrounding and threadably connected with the cylinder, a body surround- 45 ing said collar and detachable therefrom carrying laterally projecting arms, and gear engag- 50 ing rods each adjustably connected with said arms.

2. A gear puller comprising a cylinder having 55 a partition therein adjacent one end to form a forward chamber, a piston reciprocable in said chamber and extensible through the adjacent end of the cylinder, the cylinder on the other side of the partition being adapted to contain a fluid, means for pumping the fluid through said partition into the chamber for the ejection of said piston, valve-controlled means for permitting the return of the fluid from the piston chamber, a split inter- 60 iorily threaded collar surrounding the cylinder, said cylinder being provided with screw threads for connection with the collar, a member surrounding and receiving the collar, two pairs of spaced arms projecting laterally from said member, and a gear-engag- 65

ing rod adapted to be adjustably connected at one end between the arms of each pair.

3. A gear puller of the character described, comprising a cylinder of integral construction throughout and having screw-threads 70 formed upon the interior adjacent one end, a partition plate within the cylinder having connection with said threads and dividing the cylinder into a piston chamber and a fluid reservoir, a piston body within said chamber and having the inner end provided with a surrounding flange having engagement with the adjacent cylinder wall, the outer end of the chamber having means therein surrounding the piston for limiting the movement of 80 the same through contact with said flange, a head threadably engaged in the outer end of the reservoir, a tube integral with said head and extending through the reservoir end connected with said plate, said tube having a 85 valved inlet leading from the reservoir and a valved outlet at the end adjacent the plate, the plate having an aperture therein in alignment with the outlet and leading into the chamber, a piston mounted in said tube, a valve-controlled aperture formed through the plate for facilitating the return of fluid from the chamber to the reservoir, a pair of gear-engaging elements, and means for adjustably 90 securing said elements to said cylinder. 95

4. In a gear puller, an elongated body having screw-threads formed about the exterior thereof, a member movable longitudinally in said body and extensible through one end thereof for engaging the end of a shaft or similar body, means for effecting the movement of said member longitudinally of the first-mentioned body, a two-part interiorly threaded collar surrounding and having threaded engagement with the first-mentioned body, said collar having the outer wall tapered, an annular interiorly tapered body designed to receive said collar, a pair of arms carried by and extending laterally from said annular body, and a pair of rod members each having adjustable connection at one end with an arm and having its other end formed for engaging a body on said shaft. 100

5. In a gear puller, an elongated body having screw-threads formed about the exterior thereof, a member movable longitudinally in said body and extensible through one end thereof for engaging the end of a shaft or similar body, means for effecting the movement of said member longitudinally of the first-mentioned body, a two-part interiorly threaded collar surrounding and having threaded engagement with the first-mentioned body, said collar having the outer wall tapered, an annular interiorly tapered body designed to receive said collar, a pair of spaced parallel arms carried by and extending from each of two diametrically opposite points on said annular body, each pair of 110 115 120 125 130

arms having transverse recesses upon one side thereof, and a pair of rod members each having a cross-arm adjacent one end, each rod being designed to position between a pair of the first-mentioned arms with the ends of the cross-arms in the transverse recesses, the other end of each rod being formed for engaging a body carried upon the said shaft.

In testimony whereof I hereunto affix my
10 signature.

JAMES E. LYNCH.
